ROPE SPLICING SPIKE

James D. McGrew, 8120 Rio Linda Blvd.,
Elverta, Calif. 95626

Filed Oct. 29, 1971, Ser. No. 194,084

Term of patent 14 years

Int. Cl. D8—05

U.S. Cl. D8—14

FIG. 1.

FIG. 5

FIG. 2.

FIG. 4.

FIG. 3.

FIG. 1 is an exploded perspective view of a rope splicing spike, showing my new design;

FIG. 2 is a front elevational view, the rear elevation being substantially identical in appearance;

FIG. 3 is a bottom plan view;

FIG. 4 is a side elevational view of one side, the opposite side elevation being substantially identical in appearance; and

FIG. 5 is a top plan view.

I claim:

The ornamental design for a rope splicing spike, as shown and described.
